CLAIM

The ornamental design for a bottle assembly, as shown and
described.

DESCRIPTION

FIG. 1 is a perspective view showing the bottle assembly;
FIG. 2 is a front plan view of the bottle assembly wherein
a back plan view of the bottle assembly is identical to this
front plan view;
FIG. 3 is a side elevation view of the bottle assembly;
FIG. 4 is a top plan view of the bottle assembly; and,
FIG. 5 is a bottom plan view of the bottle assembly.
